(57) **CLAIM**

I claim the ornamental design for a handheld scanner, as shown.

DESCRIPTION

FIG. 1 is a rear perspective view of the handheld scanner;
FIG. 2 is a front perspective view thereof;
FIG. 3 is a left side view thereof;
FIG. 4 is a right side view thereof;
FIG. 5 is a top view thereof;
FIG. 6 is a bottom view thereof;
FIG. 7 is a rear view thereof; and,
FIG. 8 is a front view thereof.
